UNITED STATES PATENT OFFICE.

JOHN B. RETALLACK, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE TESTING SYSTEM.

Application filed May 9, 1924. Serial No. 711,970.

To all whom it may concern:

Be it known that I, JOHN B. RETALLACK, a citizen of the United States of America, residing at East Orange, in the county of 5 Essex, State of New Jersey, have invented certain new and useful Improvements in Telephone-Exchange Testing Systems, of which the following is a full, clear, concise, and exact description.

10 This invention relates to a telephone exchange system, and more particularly to a testing system for use in a manual office interconnecting with automatic offices.

15 It is an object of this invention to provide an improved testing system.

In exchange areas that include both manual and automatic offices, it is desirable to extend calls originating in the manual office to subscribers in the automatic office. In 20 some exchange areas of this type, the manual office is equipped with common apparatus to be set by an operator therein for controlling the automatic selection of an idle trunk to any automatic office and for the control 25 of the selective switches of the automatic office over the selected trunk. The trunk number is indicated to the operator by the lighting of lamps and the calling plug of a cord circuit is inserted in the trunk of that 30 number in the standard manner of completing a manual connection. The subscriber who has access to the manual office is thus quickly connected to any subscriber whose line terminates in an automatic office.

35 It is necessary for each manual operator to care for a large number of outgoing calls extending to both manual and automatic subscribers and it is apparent that the ordinary method of using a dial for the control of selective switches would be slow and reduce the number of calls handled by an operator. Therefore, register senders are included in the aforementioned common apparatus and the setting of each register for 40 any digit requires only a single momentary action by the manual operator.

The common apparatus to accomplish this purpose is of a complicated nature and the adjustment of its parts may become impaired from wear or from careless manipulation. It is therefore important that a system 45 of this nature be regularly tested in order to maintain its parts in adjustment so

that efficient service may be given to the telephone subscribers.

A feature of this invention is in the provision of a sender testing unit to establish control circuits for operating the registers of a sender and consecutively setting said registers upon one continuous revolution of 55 a switch.

A further feature of this invention is in the provision of a testing unit to test a link whose ordinary function is to select outgoing trunks to automatic exchanges and to 60 select a sender for controlling automatic switches over said trunk.

A further feature of this invention is in the provision of a testing unit to control arbitrarily trunk indicating apparatus 70 which is ordinarily functioned by the automatic selection of an idle trunk.

These and other features of the invention will be apparent from the following description taken in connection with the accompanying drawings.

While the invention has been disclosed as particularly adapted for testing apparatus associated with manual and panel type machine switching offices, it is apparent from 80 the following description that the invention has a wider utility and that by slight modifications it could be adapted for testing other types of apparatus.

Referring to the accompanying drawings, 85 Figs. 1 to 6 illustrate testing equipment for testing the apparatus and circuits shown in Figs. 7 to 16.

Fig. 1 illustrates a testing unit for testing the operation of trunk indicating apparatus 90 shown in Fig. 9.

Figs. 2 and 3 illustrate a testing unit for testing the link in conjunction with the sender apparatus shown in Figs. 7 and 10 to 16 inclusive.

Figs. 4, 5 and 6 illustrate a testing unit for testing the sender apparatus shown in Figs. 14, 15 and 16.

Figs. 7 to 16, inclusive, illustrate a switching mechanism arranged for the extension of calls from a manual office to an automatic office controlled from a manual switchboard position. This system is described in detail in the patent to Louis M. Allen, No. 1,513,-362, issued Oct. 28, 1924.

Fig. 17 illustrates the manner in which

the drawings should be arranged. The testing system drawings have been located adjacent to the parts of the switching system with which they are associated in co-operative relation. This separates the drawings of the testing system with regard to their numbering sequence.

Description of apparatus.

- 10 Referring to the apparatus used in Figs. 1 to 6, inclusive, the switch shown at 670, in Fig. 6, some of its cams being shown on both Figs. 4 and 6, is of the sequence switch type. The switch shown in Fig. 5 is of the self-interrupting step-by-step type. Keys 409 to 439, inclusive, are of the manual locking type. Keys 109 and 119, inclusive, shown in Fig. 1, are also of the manual locking type. Keys 380 to 389 inclusive, in Fig. 3 are of the non-locking type. The remainder of the apparatus is of a type well known, which will be referred to in the detailed description.

25 *Detailed description.*

Assuming that the sender portion of the key indicator system is to be tested by the apparatus of Figs. 4, 5 and 6, a testman operates key 630 to associate brushes 603, 604, 605 and 606 with cams and key contacts shown in Fig. 4. Key 630 remains locked during the test. Key 633 is now operated and released. The operation of key 633 establishes a circuit to energize switch magnet 600. This circuit may be traced from grounded battery through the winding of magnet 600, contacts of key 633, right normal contact of key 631, upper contacts of cam 612, right normal contact of relay 644, right outer normal contacts of relay 642 to ground. The energization of magnet 600 attracts its armature in such manner that, when key 633 is released to de-energize magnet 600, the brush assembly 601 to 606 is stepped forward to the first position terminals, to associate the testing equipment with conductors 660 to 665, inclusive, connected to the first sender to be tested. Following the advance of the brush assembly 601 to 606, inclusive, key 631 is operated and remains locked during the test. The operation of key 631 establishes an energizing circuit for relay 645. This circuit may be traced from grounded battery through the left winding of relay 645, left inner normal contacts of relay 642 to ground through the left contact of key 631. A ground circuit is also established from the left outer contact of key 631, through the conductor 655, left outer normal contacts of relay 543, conductor 654, to the armatures of relays 641 and 640. This ground circuit is later used as a locking path for relays 640 and 641. The operation of relay 645 establishes an obvious circuit to

operate relay 643. The operation of relay 643 establishes a circuit to operate relay 642. This circuit may be traced from grounded battery through the winding of relay 642, left contact of relay 643 to ground through the left contact of key 631. Relay 642 in operating establishes a locking circuit for itself through its left inner contact to ground through the left contact of key 631.

The operation of relay 643 further establishes a circuit from grounded battery through the right winding of relay 645, right contact of relay 643, left contact of key 630, brush 606 and its associated contact, conductor 665, to conductor 1324 of the sender to be tested. If this sender is busy, conductor 1324 is characterized by ground potential which will maintain relay 645 in an operated position. If the sender is idle or becomes idle during the association of the test circuit with the sender, conductor 1324 is not characterized by a ground potential and relay 645 is released. The release of relay 645 opens the actuating circuit for relay 643 to cause its release. The release of relay 643 associates ground potential with brush 606 to characterize the sender as busy and to establish an operating circuit for relay 1401. This circuit may be traced from ground through the right inner contacts of relay 642, right normal contact of relay 643, left contact of key 630, brush 606 and its associated contact, conductor 665, conductor 1324 and thence to grounded battery through resistance 1402 and relay 1401 operating relay 1401. The circuit paths established by the operation of relay 1401 will be described later. The operation of relay 642 further establishes a circuit to light lamp 635 as an indication that the sender to be tested is not busy. This circuit may be traced from grounded battery through lamp 635, left outer contact of relay 642, left normal contact of relay 643 to ground through the left contact of key 631.

A registration on keys 400 to 439, inclusive, is now made to establish circuits for the operation of certain of the register relays shown in Fig. 16. One of keys 400 to 409, inclusive, is operated for controlling incoming brush selection. One of keys 410 to 419, inclusive, is operated for final brush selection. The incoming group selection is dependent on the combination of the aforesaid keys along with the operation or non-operation of relay 450. One of keys 420 to 429, inclusive, is operated for final tens selection and one of keys 430 to 439, inclusive, is operated for final units selection. All of keys 400 to 439, inclusive, are of the locking type and the circuit paths remain established through their contacts to operate the register relays upon the rotation of the sequence switch cams shown in Fig. 4. When the registration keys have been set, start key

- 441 is actuated to establish an operating circuit for relay 640 which is obvious and need not be traced. The operation of relay 640 establishes a circuit to energize sequence 5 switch magnet 610. This circuit may be traced from grounded battery through the winding of magnet 610, contact of cam 611, left normal contact of relay 641, left contact of relay 640, left outer contact of relay 10 642, left normal contact of relay 643 to ground through the left contacts of key 631. The sequence switch cams make a complete revolution since master contact 670 is established in all positions except position 1. 15 Upon the rotation of the sequence switch, circuits are progressively established to control the sender and operate the various sets of register relays, as will be described later.
- The operation of relay 640 further establishes a circuit to operate relays 644 and 545. 20 The energizing circuit for relay 644 may be traced from grounded battery through its winding, left contact of relay 640, left outer contact of relay 642, left normal contact of relay 643 to ground through the left contacts of key 631. The operating circuit for relay 545 may be traced from grounded battery through its winding the left back contact of relay 547, conductor 658, and thence 25 to ground over the operating circuit traced for relay 644. A circuit is also established from this ground through brush 505 and its associated contact, lamp 530 to grounded battery to light lamp 530 as an indication 30 that brush assembly 501 to 506, inclusive, is resting in its normal position. The operation of relay 644 opens at its right contacts, the actuating circuit for magnet 600 to prevent further operation of switch magnet 40 400, since key 631 might be released previous to the completion of the test of the sender.

Assuming that the call number registered on keys 401 to 439, inclusive is 1647 45 the testman has actuated key 401, key 416, key 424 and key 437. Upon the rotation of the sequence switch to position 4, the circuit established through the contacts of key 401 becomes effective and may be traced from 50 ground through the upper contact of cam 622, resistance 444, right inner contacts of key 401, left upper contact of cam 618, contact of cam 614, conductor 651, right middle contact of key 630, brush 604, conductor 55 663, conductor 1415, brush 1412 and its associated contact, conductor 1416, left windings of relays 1602, and 1603 conductor 1613 to grounded battery at the middle left contact of relay 1403, relay 1403 having operated upon the prior operation of relay 1401. Relay 1602 operates in this circuit but due to the inclusion of resistance 444, the marginal relay 1603 remains inert. Relay 1602 locks in a circuit from ground 60 through its inner right contact and right

winding to battery on conductor 1613. Another circuit is completed from ground through the upper contact of cam 622, left inner contacts of key 401, left inner contacts of key 401, left upper contact of cam 623, contact of cam 615, conductor 652, right outer contact of key 630, brush 603, and its associated contact, conductor 662, winding of relay 1404, brush 1410 and its associated contact in its normal position, 70 conductor 1417, right winding of relay 1601 to battery on conductor 1613. Since no resistance is included in this circuit, the marginal register relay 1601 operates and locks from ground through its inner left contact 75 and left winding in series with its right winding. Relay 1600 is also energized in a circuit from grounded battery on conductor 1613, right winding of relay 1600, inner right contact of relay 1601, inner right contact of relay 1602 to ground. Relay 1404 which becomes energized completes a circuit from ground through its contact, left normal contact of relay 1407, right normal contact of relay 1400, contact and winding of 80 stepping magnet 1408 to grounded battery. Relay 1406, which is energized in parallel with the stepping magnet, closes a locking circuit for itself including the contact of magnet 1608 and also closes a holding circuit for magnet 1608 independent of the contact relay 1604. The magnet 1608 becomes energized and when its armature is fully attracted, the circuit of relay 1406 is opened 85 and the relay becomes deenergized to open 90 the circuit of magnet 1408. Magnet 1408 releases and advances the brushes of the register control switch forward one step.

When brushes 1409 to 1414, inclusive, of the register control switch reach position 1, 105 a circuit is closed from grounded battery through the winding of relay 1503, left normal contacts of relay 1502, conductor 1516, brush 1409 to ground. Relay 1503 operates and closes a circuit from ground through its inner left contact, conductor 1517 and thence in parallel through the resistance 110 1402 and winding of relay 1401 to grounded battery.

Upon the further rotation of the sequence switch 670 to position 5, circuits are established through the contacts of key 416. A circuit is thus established from the ground through the upper contact of cam 622, resistance 444, right inner contacts of key 115 416, right upper contact of cam 618, contact of cam 614, conductor 651, right middle contacts of key 630, brush 604 and its associated contact, conductor 663, conductor 1415, brush 1412 and its associated contact, conductor 1416, left winding of relay 1605, left winding of relay 1606 to grounded battery on conductor 1613. Relay 1605 operates and locks through its right winding but the relay 1606 is marginal and remains unoper- 120 125 130

ated. Another circuit is established from ground through the upper contact of cam 622, left inner contacts of key 416, left upper contact of cam 616, contact of cam 613, conductor 650, right inner contact of key 630, brush 605 and its associated contact, conductor 664, winding of relay 1405, brush 1410, conductor 1419, right winding of relay 1604, to grounded battery on conductor 1613. Relay 1604 operates and locks through its inner left contact and both winding in series. Relay 1405 is also energized to cause the advance of the register control switch in the manner above described from position 1 to position 2. Relay 1405 further establishes a circuit from ground through its contact, normal contact of relay 1404, brush 1414, conductor 1420, right winding of relay 1607 to grounded battery on conductor 1613. Relay 1607 operates and locks through its left winding and left contact.

Upon further rotation of the sequence switch to position 6, circuits are established through the contacts of key 424. A circuit is established from ground, through the lower left contact of cam 622, left contact of key 442, right inner contacts of key 424, right lower contact of cam 619, cam 614, conductor 651, right middle contacts of key 630, brush 604 and its associated contact conductor 663, conductor 1415, brush 1412 and its associated contact, conductor 1421, left winding of relay 1614, left winding of relay 1609, conductor 1615, inner left contact of relay 1403 to grounded battery. Relays 1614 and 1609 operate and lock through their right windings. Another circuit is established from ground through the lower left contact of cam 622, left contact of key 442, resistance 443, left contact of key 424, right lower contact of cam 621, contact of cam 615, conductor 652, right outer contact of key 630, brush 603 and its associated contact, conductor 662, winding of relay 1404, brush 1410, conductor 1422, right winding of relay 1608, conductor 1613 to grounded battery. Relay 1404 operates in the circuit traced. Relay 1608 is marginal and remains inactive. In the manner previously described, the relay 1404 establishes a circuit to advance the register control switch to its third position.

Upon further rotation of sequence switch 670, to position 7, circuits are established through the contacts of key 436. A circuit is established from ground through the lower left contact of cam 622, left contact of key 442, left contact of key 636, right lower contact of cam 617, contact of cam 613, conductor 650, right inner contacts of key 630, brush 605 and its associated contact, conductor 664, winding of relay 1405 brush 1410 and its associated contact, conductor 1423, right winding of relay 1610, conductor 1615 to grounded battery. Relay

1610 operates over the circuit traced and locks through both of its windings. Relay 1405 operates and establishes a circuit through its contact and the normal contact of relay 1404, brush 1414, and its associated contact, conductor 1424, right winding of relay 1612, conductor 1615 to grounded battery. Relay 1612 operates in the circuit traced and locks through its left winding and left contact. Relay 1405 establishes a circuit to advance the brush assembly of the register control switch from position 3 to position 4. When brush 1409 of the control switch is advanced from position 3, the previously traced circuit of relay 1503 is opened and the relay deenergized. At the time that relay 1503 operates following the registration of the first digit, a circuit is established from battery through the stepping magnet 1513 of the sender control switch, contact of said magnet, outer left contact of relay 1503, to ground through brush 1509 and its associated contact. Magnet 1513 interrupts its own circuit and advances the brushes of the sender control switch to their zero position terminals, which is the first position of the switch. In this position, the fundamental circuit is established between the sender and the testing circuit. Under ordinary operating conditions this fundamental circuit is established through a selective switch to control brush selection. The fundamental circuit may be traced from grounded battery through the winding of relay 547 brush 506 and its associated contact, left inner contacts of relay 544, left outer contacts of relay 644, brush 602 and its associated contact, conductor 661, brush 1507 and its associated contact, windings of stepping relay 1500, left winding of overflow relay 1506, left contacts of the 0' counting relay conductors 1518 and 660, brush 601 and its associated contact, left inner contact of relay 644, conductor 657, right inner contact of relay 544, resistance 511 to ground. Stepping relay 1500 and relay 547 operate in the fundamental circuit traced. The effect of the operation of the stepping relay will be described later. The operation of relay 547 establishes a circuit to energize test switch magnet 500. This circuit may be traced from grounded battery through the winding of magnet 500, brush 504 and its associated contact, left contact of relay 547, left contacts of relay 640, left outer contact of relay 642, left normal contact of relay 643 to ground through the left contacts of key 631. The test switch brush assembly 501 to 506 inclusive, now rotates from position 1 to position 2, and the energizing circuit for magnet 500 is opened upon the rotation of the switch. In the second position of the switch a locking circuit is established for relay 547 which may be traced from grounded battery through its

winding and right contact, brush 506 and its associated contact and thence to ground over the fundamental circuit, as previously traced. Upon the rotation of the test switch 5 out of its position 1, lamp 530 is extinguished and a circuit is established to light lamp 531 to indicate the position of the switch. This circuit is the same as that traced to light lamp 530. In position 2 of 10 the test control switch, a circuit is further established to operate relay 549. This circuit may be traced from grounded battery through the winding of relay 549, to ground through brush 503 and its associated contact. 15 The operation of relay 549 establishes a number of battery connections in circuit with the windings of the counting relays to be used upon the operation of said relays. The operation of relay 549 further establishes 20 a circuit to light lamp 570 as a progress indication. A circuit is also established to operate relay 541 which may be traced from grounded battery through its winding, normal contacts of relay 542, conducting segment of interrupter 563, brush 504 and its associated contact, left contact of relays 547, conductor 658, left contact of relay 640, left outer contact of relay 642, left normal contact of relay 643 to ground through the 25 left contacts of key 631. Interrupter 563 is constantly rotating and during the period that an operating circuit is established for relay 541, a shunt ground circuit is also established to prevent the operation of relays 540 and 542. Upon further rotation of 30 the interrupter 563 this shunt ground is removed to cause the operation of relays 540 and 542 in series with the winding and contact of relay 541. The operation of relay 541 establishes a locking circuit for itself which is maintained as an operating and holding circuit for relays 540 and 542.

Let it be assumed that the registers of the sender have been operated in accordance with the control setting of the register keys shown in Fig. 4. This setting is the same as would be made upon the registers for a call to a subscriber's line. A test of register settings will now be described and the sender apparatus will control the testing apparatus, instead of selective switches as it does in a call to a subscriber's line. The testing apparatus also controls the progressive operation of the sender. The control of selective switches by a sender is well known in the art, therefore, it may be stated that interrupter 563 in this testing system simulates a selector switch commutator and relay 547 simulates a relay ordinarily used in selective switches for controlling the upward movement of the elevator and commutator brushes.

It will be remembered that the fundamental circuit was traced through the windings of relay 1506 and relay 1500. Relay 1506 is a polarized relay and the direction of current flow in the circuit traced is not in the proper direction for the operation of the relay. The stepping relay 1500, however, operates and establishes a circuit from 70 ground through its contact, brush 1508, conductor 1519, right normal contact of relay 1615, outer right front contact of relay 1600, left normal contact of relay 1603, conductor 1616, thence through the corresponding conductor 1520, conductor 1521, brush 1512, conductor 1522, winding of 0 counting relay to grounded battery. The 0 counting relay operates and establishes a circuit from 75 grounded battery through its winding and the winding of the 0' counting relay in series, contact of the 0 counting relay, conductor 1523, brush 1510 to ground. Upon the rotation of interrupter 563 a ground shunt is associated with the fundamental circuit to release the stepping relay 1500. The shunt path may be traced from ground through the left contacts of key 631, left normal contact of relay 643, left outer contact of relay 642, left contact of relay 640, left contact of relay 547, brush 504 and its associated contact, interrupter 563, contact of relay 540 where a junction is established with the fundamental circuit to release 80 stepping relay 1500 and maintain relay 547 in an operated position. At the same time that the shunt circuit is established through interrupter 563, a circuit is established from the ground traced to the interrupter, thence through the contact of relay 542, contact of 85 the 10' counting relay, winding of the 10 counting relay, right outer contacts of relay 549 to grounded battery operating the 10 counting relay. Relay 10 now locks in series with 10' but 10' being shunted at the interrupter 563 does not operate. The release of stepping relay 1500 removes the shunt from the winding of counting relay 0' to cause 90 its operation in series with the number 0 counting relay. Upon further rotation of interrupter 563 to a non-conducting segment, the shunt is removed from the number 10' counting relay to cause its operation in series with the number 10 counting relay. The operation of the 0' counting relay in 95 the sender opens the fundamental circuit to cause the release of relay 547 which is effective as soon as interrupter 563 rotates to an insulated segment. The release of relay 547 opens the ground circuit associated with interrupter 563 so that no further counting relays in the testing circuit will be operated and therefore a record has been made in the testing circuit of the number of counting 100 relays that were operated in the sender.

The testman may now operate a key corresponding to the registration originally made on the keys 400 to 409 of Fig. 4. The key operated for this registration is key No. 520. A circuit is thus established to operate lamp 105 120 125 130

571 to indicate that the correct number of counting relays have been operated in the sender circuit. The circuit for lighting lamp 571 may be traced from grounded battery through the left outer contacts of relay 549, lamp 571, contacts of key 520, normal contact of the number 11 counting relay to ground through the contact of the number 10 counting relay.

10 The operation of the 0' counting relay in the sender establishes a circuit to energize magnet 1513 to advance the sender control switch. This circuit may be traced from grounded battery through the winding and contact of magnet 1513, the right inner contacts of relay 1505, right contact of the 0' counting relay to ground through brush 1510 and its associated contact. The sender switch now rotates its brush assembly to the terminals of the next adjacent position. The rotation of the sender switch opens the holding circuit of the counting relays to cause their release. In this position of the sender switch, a circuit is again established to 20 actuate the magnet 1513 from grounded battery through its winding and contact, outer contact of relay 1504 to ground through brush 1510 and its associated contact. The brush assembly advances to its second control position.

30 It will be remembered that the release of relay 547 was occasioned by the opening of the fundamental circuit. The release of relay 547 establishes a circuit to operate relay 545. This circuit may be traced from grounded battery through the winding of relay 545, left normal contact of relay 547, left contact of relay 640, left outer contact of relay 642, left normal contact of relay 643 to ground through left contacts of key 631. The operation of relay 545 establishes a circuit to advance the test control switch. If the number of counting relays operated in the testing circuit Fig. 5, agrees with the 40 setting of the register key, this circuit may be traced from grounded battery through the winding and contacts of magnet 500, contacts of relay 545, brush 501 and its associated contact, left outer contacts of key 401, conductor 470 of Figs. 4 and 5, contact of key 520 in its normal position, normal contact of the number 11 counting relay to ground through the contact of the number 10 counting relay. It will be noted that if 50 two sets of counting relays were operated, the circuit traced would be opened at the contacts of the number 11 counting relay, and a circuit would not be established to energize magnet 500. The testman upon observing that the test has stopped may operate any of keys 520 to 529 inclusive. When the key is operated corresponding to the last set of counting relays operated, a circuit is established to light the lamp associated with that key to indicate the un-

standard condition of the sender register. The operation of switch magnet 500 rotates the brush assembly to its third position. Upon the rotation of the brush assembly, the holding circuit for the counting relays Fig. 5 and relays 540, 541 and 542 is opened to cause their release, lamp 531 is extinguished and a circuit established to light lamp 536 as an indication that the test switch has advanced as a result of a correct functioning of the sender under test. In this position of the switch the fundamental circuit is again established to operate relays 547 and the stepping relay 1500. The operation of relay 547 opens the energizing circuit for relay 545 to cause its release. A circuit is further established to energize the test switch magnet which may be traced from grounded battery through the winding and contacts of magnet 500, brush 504 and its associated contact, left contact of relay 547, left contact of relay 640, left outer contact of relay 642, left normal contact of relay 643, to ground through the left contacts of key 631. The test switch brush assembly now advances to its second control position. In this position of the switch a circuit is again established to operate relay 549 to associate grounded battery with the operating circuits of the counting relays and also to establish a circuit to light lamp 570 as a check indication of the positioning of the test switch and the released condition of the counting relays. The advance of the test switch further establishes a holding circuit for relay 547 over the fundamental circuit, as previously traced.

60 A check has now been made of the register relays positioned by the register key for incoming brush selections. The check of the register relays positioned for incoming group selection is the next to be made. It will be noted that upon the rotation of the test switch brush 502, a circuit is established to operate relay 450 from grounded battery through its windings, left outer contact of key 416 to ground through brush 502 and its associated contact. Upon the operation of the testing unit counting relays and the sender counting relays, the fundamental circuit is opened the same as for the check of brush selection which occasions the release of relay 547. The release of relay 545 establishes a circuit to operate relay 545 in the manner previously described. The operation of relay 545 partly prepares a circuit to advance the test control switch and if the number of counting relays operated in the testing circuit agrees with the setting of the register keys a circuit for advancing the test control switch is completed. This circuit may be traced from grounded battery through the winding of magnet 500 contact of relay 545, brush 501 and its associated contact, conductor 590, right outer contact of key

401, right contact of relay 450, conductor 591, contact of key 523, normal contact of counting relay 14, contacts of counting relays 13, 12, 11 and 10 to ground. The operation of switch magnet 500 rotates the brush assembly one position. Upon the rotation of the brush assembly, the holding circuit for the counting relays, Fig. 5, is opened to cause their release and a circuit is again established to light lamp 536 as an indication that the test switch has advanced as a result of a correct functioning of the sender under test. In this position of the switch, the fundamental circuit is again established to operate relays 547 and the stepping relay 1500. The operation of relay 547 opens the energizing circuit for relay 545, to cause its release. A circuit is therefore established to energize the test switch magnet as previously described and the test switch brush assembly is advanced to its third control position. In this position of the test switch, a check of final selector brush selection is made in the manner described for incoming brush selection and succeeding tests for final selector tens selection and final selector units selection are made in this same manner. The path for energizing the test switch magnet 500 as a check of the sender control of final selection is made through the contacts of keys 416, 424 and 437. In this manner, the settings of the register relays are progressively checked by the testing circuit until the completion of final selector units selection.

Upon the completion of the check of final selector switch units selection, relay 547 is released as previously described. The release of relay 547 establishes a circuit to operate relay 545 as previously described. The operation of relay 545 establishes a circuit through the registration keys to operate magnet 500 which advances the test control switch from position 10 to position 11. The advance of the test control switch brush assembly, opens the actuating circuit for relay 549 to release the counting relays including relays 540, 541 and 542. In this position of the switch, a circuit is established to operate relay 544 from grounded battery through its winding to ground through brush 503 and its associated contact. Relay 544 in operating establishes a locking circuit for itself through its left outer contacts to ground through brush 502 and its associated contacts. The operation of relay 544 establishes a circuit to rotate the test switch from position 11 to 12. The circuit to energize magnet 500 for this purpose may be traced from grounded battery through the winding and contacts of magnet 500, contacts of relay 545, brush 501 and its associated contact, right outer contact of relay 544 to ground through brush 502 and its associated contact. A further function of relay 544 is to reverse battery and ground potential with relation to the fundamental circuit. This simulates the well known operation of the reversing of potential in a selective switch to control a sender. Relays 547, 1506 and 1500 are operated from the reversed battery potential applied to the fundamental circuit. Relay 1506 is a polarized relay and the current flow is now in the proper direction for its operation whereupon it locks in a circuit from grounded battery through its right winding and contact brush 1509 and its associated contact to ground. Relay 1506 further establishes a circuit from grounded battery through the winding of relay 1505, contact of relay 1506 and thence to ground through brush 1509 and its associated contact. Relay 1505 completes a circuit from grounded battery through the windings of the 0 and 0' relays 1514 and 1515 in series, left outer contacts of relay 1505 to ground through brush 1509 and its associated contact. A circuit is thereupon established from grounded battery through the winding of relay 1502, right inner contact of relay 1505, right contact of relay 1515, left contact of relay 1514, outer left contact of relay 1505 to ground through brush 1509 and its associated contact. Relay 1502 establishes a circuit from grounded battery through its right contact, conductor 1524, right winding of relay 1407 to ground. Relay 1407 is energized and locks in a circuit from ground through its right winding and right inner contact to grounded battery through the innermost left contact of relay 1403. The operation of relay 1407 establishes a circuit from grounded battery through the winding and contact of magnet 1408, right normal contacts of relay 1400, left front contact of relay 1407, conductor 1516, left contacts of relay 1502, right contact of relay 1503, conductor 1525, brush 1409 and its associated contact to ground. A circuit is now established to operate magnet 1408 to advance the register control switch to its fifth position contacts. In position 5 of the register control switch, a circuit is established from grounded battery through the right winding of relay 1400 to ground through brush 1409 and its associated contact. Relay 1400 operates and opens the energizing circuit for relay 1401. The release of relay 1401 permits the release of relay 1403. Relay 1400 does not release since a circuit is quickly established to maintain it energized through its left winding, outermost left contact of relay 1403, conductor 1427 to ground through brush 1509 and its associated contact.

A circuit is established through the contacts of relay 1400 to energize switch magnet 1408 from grounded battery through the winding and contacts of magnet 1408, right contact of relay 1400, inner right contact of

relay 1403 to ground through brush 1413 and its associated contact. Magnet 1408 interrupts its own circuit and advances the brushes of the register control switch from 5 position 5 to position 7 where the operating circuit is opened and the switch is arrested in its rotary movement. A circuit is further established through the contacts of relay 1400 to energize magnet 1513 from 10 grounded battery through the winding and contact of magnet 1513, conductor 1426, inner left contacts of relay 1400, outermost left contacts of relay 1403, conductor 1427 to ground through the brush 1509 and its 15 associated contacts. Magnet 1513 interrupts its own circuit and advances the brushes of the sender control switch into their normal position. Relays 1506, 1505, 1502 and the counting relays are deenergized at the time 20 brush 1509 is advanced to its normal position. The register relays which have been held in a locked position are now released upon the deenergization of relay 1403 and the removal of battery potential from conductors 1615 and 1613.

The operation of relay 547, in the fundamental circuit as last traced, establishes a circuit to operate the test switch magnet 500. This may be traced from grounded battery 30 through the winding and contacts of magnet 500, brush 504 and its associated contact, left contact of relay 547, left contact of relay 640, left outer contact of relay 642, left contact of relay 643 to ground through 35 the left contacts of key 631. The test switch now rotates from its position 12 to 13 and in thus rotating opens the fundamental circuit to release relay 547. In position 13, a circuit is established to operate counting 40 register 560. This circuit may be traced from grounded battery through the winding of register 560, brush 505 and its associated contact to ground through the left contacts of key 631 over the circuit previously 45 traced. The operation of register 560 establishes a circuit from ground through its contact and through the contacts and winding of switch magnet 500 to grounded battery, operating magnet 500. The test switch 50 is now rotated from its position 13 to 14. In this position of the switch, relay 546 is operated from grounded battery through its winding, brush 505 and its associated contact and thence to ground over a circuit 55 previously traced through the left contacts of key 631. The operation of relay 546 establishes a circuit to light lamp 538 from ground through its right contacts, lamp 538 to grounded battery. If lamp 538 remains 60 lighted it denotes that the sender switch did not advance properly to its second normal position. Should the sender switch not rotate to its second normal position a circuit is established to operate relay 1501 in the

sender and relay 547 in the testing circuit. 65 The circuit for operating relay 1501 may be traced from grounded battery through its winding, left inner normal contacts of relay 1504 to ground through brush 1510 and its associated contact. The circuit for operating relay 547 may be traced from grounded battery through its winding brush 506 and its associated contact, right inner contact of relay 544, which has remained in the operated position, left inner contact of relay 644, brush 601 and its associated contact conductor 660, contacts of the sender 0' counting relay, windings of relays 1506 and 1500, brush 1507 and its associated contact, contacts of relay 1501, conductors 1425 and 661, brush 602 and its associated contact, left outer contacts of relay 644, left inner contacts of relay 544, resistance 551 to ground. The operation of relay 547 establishes a circuit to energize switch magnet 500, which may be traced from grounded battery through the winding and contacts of magnet 500, brush 504 and its associated contact, left contacts of relay 547 and thence 70 to ground through the left contacts of key 631 over a circuit previously traced. The test switch now rotates from position 14 to 15 and thus establishes a circuit to light lamp 539 which may be traced from grounded battery through lamp 539, brush 505 and its associated contact and thence to ground through the left contacts of relay 631 over a circuit previously traced. Lamp 539 denotes that the sender switch did not rotate 75 to its normal position and thus denotes an 80 unstandard condition in the sender.

The testing circuit switch is restored to normal from either position 14 or 15 by the operation of key 440, which establishes an obvious circuit to operate relay 543. 95 Relay 543 in operating establishes a locking circuit for itself from grounded battery through its left winding, left inner contact and right contact to ground through brush 502 and its associated contact. A circuit 100 is further established to continuously energize magnet 500 until the switch has restored to normal. This circuit may be traced from grounded battery through the winding and self-interrupting contact of 105 magnet 500, right contact of relay 543 to ground through brush 502 and its associated contact. When the switch has restored to normal the locking circuit or relay 543 is 110 opened to cause its release. It will further be noted that the operation of relay 543 opened at its left outer contact the holding circuit for relay 640 and 641. The release of relay 640 opens the holding circuit for 115 relay 644 to cause its release. The rotation of the test switch to normal, opens the locking circuit for relay 544 to cause its release. The testman now releases key 631 prepara- 120 125

tory to reoperating the registration keys for the test of a second sender.

Test of link and trunk selecting circuit.

5 A detail description of the link and trunk selecting circuit is given in patent to Louis M. Allen No. 1,513,362, granted Oct. 28, 1924. The description of the testing of the link and trunk selecting circuit will only 10 describe such operation as is necessary for control and test purposes. An allotter shown on Fig. 7 is used in conjunction with the testing circuit shown on Fig. 3. This allotter may be an allotter used in regular 15 service or an emergency allotter not in service, but the same as the one shown in Fig. 7.

The testman associates the testing circuit shown on Fig. 3 with the link circuit shown on Figs. 10, 11, 12 and 13 by the use of 20 patching cords. Plug 306 is inserted in jack 301, plug 316, in jack 1070; plug 307 in jack 302, plug 317 in jack 1071; plug 308 in jack 303, plug 318 in jack 1072; plug 310 in jack 305 and plug 320 in jack 1074. The 25 link to be tested is selected through the allotter circuit, Fig. 7, by a series of operations of key 300. The circuit established by the operation of key 300 energizes the control magnet of the allotter switch 700. 30 This circuit may be traced from grounded battery, through the winding of magnet 701, sleeve of jack 1070, sleeve of plug 316, sleeve conductor of patching cord 311, sleeve of plug 306, sleeve of jack 301, to ground 35 through the contact of key 300. The release of key 300 deenergizes magnet 701 to cause the switch brush assembly to be propelled forward one terminal. Each subsequent operation and release of key 300 advances 40 the allotter switch brush assembly one terminal until the terminal is reached which is associated with the link to be tested. Key 346 is actuated and one of keys 341 to 345, inclusive, is actuated. The one of keys 45 341 to 345 to be actuated depends upon the position finder switch to be actuated in the link. Let it be assumed for this test that position finder switch 1000 is the one to be used. Therefore, key 345 is operated to prepare 50 an operating circuit for relay 1008. When this has been done, key 333 is actuated to establish an operating circuit for relay 340. Key 333 is a locking key and remains 55 operated. The link to be tested may be in use and thus it will be characterized by a busy ground potential impressed upon conductor 1060 which is associated with conductor 391 in the testing circuit. The operating 60 circuit for relay 340 may be traced from ground through the left contact of key 333, winding of relay 340 to grounded battery through the right contact of key 333 and resistance 321. If the link circuit is busy the 65 ground impressed upon conductor 391 effectively shunts the current from the wind-

ing of relay 340, so that it does not receive sufficient current to operate. When the link to be tested becomes idle or is idle when key 333 is operated the shunt circuit is not established and, therefore, relay 340 is operated. An obvious circuit is established to light lamp 339, through the left outer contact of relay 340 to indicate to the testman that the link circuit to be tested is idle. The 70 operation of relay 340 completes the circuit of relay 1008 and further establishes a circuit to energize magnet 701 in the allotter. 75

The circuit for energizing relay 1008 may be traced from grounded battery through the winding of relay 1008, brush 707 and its 80 associated contact, the ring spring of jack 1072, the ring conductor of plug 318, patching cord 313 and plug 308, the ring spring of jack 303, conductor 392, contacts of keys 345 and 346, left inner contacts of relay 340 85 to ground through the left outer normal contact of relay 335. The operation of relay 1008 establishes a locking circuit for itself from grounded battery through its winding and left inner contact to ground at the contact of relay 1021. 90

The energizing circuit for magnet 701 may be traced from ground, through the right contact of relay 340, sleeve of jack 303, 95 sleeve conductor of plug 308, patching cord 313 and plug 318, sleeve of jack 1072, conductor 1060, contact and winding of switch magnet 701 to grounded battery. The allotter switch now rotates to the next idle 100 link, allotting such link for the next call.

Plug 309 is now inserted into jack 304 and plug 319 is inserted into jack 1073. The actuation of the springs in jack 1073 connect a busy ground to conductor 716 and the allotter terminal associated with the hunting 105 brush 702. The link is thus maintained busy to prevent its seizure for service during test.

The operation of relay 1008 further establishes a circuit from ground through its outer right contact, a conductor 1035, 110 left normal contact of relay 1020, thence in parallel through the winding of relay 1019 to grounded battery and over conductor 1036, through the left winding of relay 1308 to grounded battery. Relay 1019 operates and locks in a circuit from grounded battery through its winding and left inner contact conductor 1030, left normal contact of relay 1309, left normal contact of relay 1310, conductor 1323, outer left normal contact 115 of relay 1025 to ground. Relay 1308 also energizes and locks in a circuit from grounded battery through its right winding and right inner contact to ground through the right normal contact of relay 1309. 120

Relay 1019 establishes a circuit from grounded battery through the winding of relay 1020, right inner contact of relay 1019 to ground. Relay 1020 operates and locks 125 in a circuit from grounded battery through 130

its winding and left inner contact, conductor 1035 to ground at the right outer contact of relay 1008. Relay 1020 establishes a circuit from grounded battery through the left 5 winding of relay 1022, left inner normal contact of relay 1023, right outer contact of relay 1020 to ground. Relay 1022 is energized in the circuit traced and locks in a circuit from grounded battery through its 10 right winding and right contact, right inner contact of relay 1008, brush 1001 and its associated normal position contact, right outer contact of relay 1008 to ground. The operation of relay 1022 further establishes 15 a circuit to operate relay 1023 from grounded battery through the right winding of relay 1023, left contact of relay 1022, contact of relay 1021 to ground. The operation of relay 1023 establishes a locking circuit for 20 itself from grounded battery through its left winding and the right outer contact of relay 1020 to ground. The operation of relays 1022 and 1023 establishes a circuit to energize switch magnet 1007. Switch 25 1000 is now rotated to find the set of terminals allotted for link testing purposes. The energizing circuit for magnet 1007 may be traced from grounded battery, through the winding and contact of said magnet, right 30 inner contact of relay 1008, right contact of relay 1023, left contact of relay 1022, contact of relay 1021 to ground. Magnet 1007 interrupts its own circuit and advances the brushes 1001 to 1006, inclusive, from position 35 to position in the direction indicated by the arrows. The test brush 1001 tests the condition of the successive operators' positions. The terminals with which brush 1001 cooperates represent the non-calling or 40 calling operators' positions. As described in the patent to Louis M. Allen hereinbefore mentioned, a terminal associated with a non-calling position is characterized by the absence of ground and a terminal associated 45 with a calling position is characterized by ground. The ground potential serves to maintain the holding circuit for relay 1022 previously traced. When, however, the brush 1001 reaches a terminal of a calling 50 operator's position or the test terminal, no ground potential will be found thereon and, therefore, the holding circuit for relay 1022 is open and this relay becomes deenergized. The deenergization of relay 1022 opens the 55 operating circuit of the stepping magnet 1007, whereby the switch 1000 is arrested in its rotary movement.

Assuming that switch 1000 has reached the twentieth position which is the test position, the release of relay 1022 establishes a 60 circuit to operate relays 1024 in the link and 335 in the test circuit. This circuit may be traced from grounded battery, through the winding of relay 335, lower contact of key 65 358, upper contact of key 359, ring spring

of jack 304, ring of plug 309, patching cord 314 and plug 319, ring spring of jack 1073, brush 1001 and its associated contact, right inner continuity contact of relay 1008, right normal contact of relay 1022, winding of relay 1024, right outer contact of relay 1019 to ground through the left outer contact of relay 1023. The operation of relay 1024 establishes a circuit to operate relay 1026 from grounded battery through the winding of relay 1026, contact of relay 1024 to ground through the left outer normal contact of relay 1025. The operation of relay 1026 establishes an energizing circuit for relay 1025 from grounded battery, through its winding and the winding of relay 1025, right contact of relay 1026, conductor 1037, right normal contact of relay 1310 to ground through the left inner left contact of relay 1308. The operating circuit for relay 1025 is not effective at this time since it is shunted by the direct circuit traced from battery through the winding of relay 1026 and the contact of relay 1024 to ground through the left outer normal contact of relay 1025. With relay 1026 operated a circuit is established from grounded battery through the right normal contact of relay 1025, left contact of relay 1026, winding of relay 1027 to ground. The utility of relay 1027 will be described later. The operation of relay 335 previously described establishes an obvious circuit to light lamp 336 as an indication that the test circuit has been selected by the position switch of the link, and a circuit for relay 337. Relay 337 locks over its inner left contact to ground at the lower normal contact of key 359.

Patching plug 366 is now inserted in jack 351 and plug 371 is inserted in jack 1250. Also plug 365 is inserted in jack 350 and plug 367 is inserted in jack 1251. The aforementioned jacks and plugs associate the testing circuit in operative relation with the trunk selecting unit of the switching system. Plug 220 is inserted in jack 390 to associate the trunk indicating apparatus of the testing circuit with the testing apparatus shown in Fig. 3. A circuit is now established to operate relay 1253 from grounded battery, through its winding, sleeve of jack 1251, sleeve of plug 367, sleeve of patching cord 369, sleeve of plug 365, sleeve of jack 350 to ground through the outer left contact of relay 337. It may be here stated that upon the operation of relay 1308 a circuit was established to operate relay 1211 in the manner described in the application to Louis M. Allen hereinbefore mentioned. The operation of relay 1211 establishes a circuit to operate relay 1028. The operation of relay 1253 now opens the energizing circuit for relay 1211 to cause its release and the release of relay 1211 opens the energizing circuit for relay 1028 to cause its release.

The test man now operates apparatus to actuate the trunk selecting circuits, Figs. 11 and 12, in order to select a particular trunk for example trunk No. 31. To do this, key 362 is operated to establish an energizing circuit for magnet 1101 from grounded battery, through the winding of magnet 1101 and its lower contact, brush 1123 and its associated contact, conductor 1220, left inner contact of relay 1253, tip spring of jack 1250, tip of plug 371, patching cord 370 and plug 366, tip spring of jack 351, contact of key 362, left contact of key 347, left outermost contact of relay 353 to ground through the left outer contact of relay 335. It will be noted that the circuit traced is carried through the self-interrupting contact of switch magnet 1101 to cause the switch brush assembly to continue its operation until said brushes have approached the trunk to be associated with the testing circuit. Key 362 is then released and key 355 is actuated in order to step the switch brush assembly one terminal for each operation of the key to select a particular trunk. Each operation and release of key 355 advances the brush assembly one terminal by holding the magnet 1101 in an operated position until the key is released. The circuit for doing this may be traced from grounded battery, through the winding of magnet 1101, brush 1122 and its associated contact, conductor 1219, sleeve of jack 1250, sleeve of plug 371, cord 370 and plug 366, sleeve of jack 351, contact of key 355, left outer contact of key 347, left outermost normal contact of relay 353 to ground through the left outer contact of relay 335. The operation and release of key 355 is continued until the trunk is selected.

The test man now operates key 354 to establish a circuit for the operation of relay 353, over a circuit from grounded battery, through the winding of relay 353, contact of key 354 to ground through the left inner contact of relay 335. Relay 353 establishes a locking circuit for itself through its right contact to ground through the contact of key 358. The operation of relay 353 further establishes a circuit to operate relay 1211 which may be traced from grounded battery through the left middle contact of relay 353, ring spring of jack 350, ring of plug 365, patching cord 369 and plug 367, ring spring of jack 1251, winding of relay 1211, right inner contact of relay 1253, ring spring of jack 1250, ring of plug 371, cord 370 and plug 366, ring spring of jack 351 to ground through the left inner contact of relay 353. The operation of relay 1211 establishes a circuit to light lamp 363 to indicate its satisfactory operation. This circuit may be traced from grounded battery, through lamp 363, tip spring of jack 350, tip of plug 365, cord 369 and plug 367, tip of

jack 1251 and thence to ground through the left outer contact of relay 1211. The operation of relay 1211 further establishes a circuit to operate relay 1028 from grounded battery, through the winding of relay 1028, right inner contacts of relay 1027, to ground through the left outer contact of relay 1211. The operation of relay 1028 associates through its third and fourth left outer contacts, the trunk selecting circuit with the trunk indicating circuit shown in test circuit Fig. 2, which circuit is now operated, to indicate the number of the trunk to which the selector is connected.

Upon the operation of relay 1028 a circuit is established from ground, through the right-hand high resistance winding of relay 1212, brush 1127 and its associated contact, conductor 1223, left inner contact of relay 1214, conductor 1225, third left contact of relay 1028, brush 1003 and its associated contact, ring spring of jack 1070, ring of plug 316, patching cord 311 and plug 306, ring spring of jack 301, ring spring of jack 390, ring of plug 220, right back contact of relay 202, right windings of relays 204 and 206 to grounded battery. Relay 204 operates in the circuit traced, but on account of the high resistance of the right-hand winding of relay 1212, the marginal relay 206 remains inert. Relay 204 locks in a circuit from grounded battery, through its left winding and left contact, sleeve of plug 220, sleeve of jack 390 to ground through the left outer contact of relay 335. This same ground establishes a circuit to operate relay 230 through the left outer normal contact of relay 202, winding of relay 230 to grounded battery. The utility of relay 230 will be described later. Simultaneous with the establishment of the circuit to operate relay 204, a circuit is established from ground, through the left low resistance winding of relay 1212, brush 1126 and its associated contact, conductor 1222, left outer contact of relay 1214, conductor 1224, fourth left outer contact of relay 1028, brush 1002 and its associated contact, tip spring of jack 1070, tip of plug 316, patching cord 311 and plug 306, tip spring of jack 301, tip spring of jack 390, tip of plug 220, left inner normal contact of relay 202, right winding of relay 203, right winding of relay 205 to grounded battery. Since the left inner winding of relay 1212 is of low resistance, the sensitive relay 203 and the marginal relay 205 are operated. Relays 203 and 205 lock from grounded battery, through their left windings and left inner contacts to ground through the sleeve of jack 220 as previously traced. Upon the operation of relays 203 and 204 a circuit is established to operate relay 218 from grounded battery, through its winding to ground at the left outer contact of plug 365, cord 369 and plug 367, tip of

tact of relay 203 and the right contact of relay 204. Relay 218 is slow to energize to insure complete operation of the sensitive and marginal relays before the contact is opened through which these relays operate. The operation of relay 218 establishes a circuit to operate relay 202 from grounded battery, through the winding of relay 202, contact of relay 218 to ground through the left outer contact of relay 203 and the right contact of relay 204. The operation of relay 202 is for the purpose of transferring the trunk selecting circuit conductors from the tens and hundreds indicating relays to the units indicating relays in the display circuit, Fig. 2. Upon the establishment of a circuit path through either winding of relay 1212, its operation takes place to establish an obvious energizing circuit for relay 1213. The operation of relay 1213 establishes a locking circuit for itself through its right contact, conductor 1230 to ground through the left innermost contact of relay 1028. The operation of relay 1213 further prepares a path for the operation of relay 1214 upon the release of relay 1212. The utility of this will be described later.

The operation of relay 202 releases relay 230 to establish a ground path for the relay operation to be described. The operation of relay 202 further opens the energizing circuit for relay 1212 to cause its release. The release of relay 1212 establishes a circuit to operate relay 1214 from grounded battery, through the winding of relay 1214, left contacts of relay 1213 to ground through the normal contact of relay 1212. The operation of relay 1214 transfers conductors 1224 and 1225 from conductors 1222 and 1223 leading to the side switch brushes 1126 and 1127 and connects them to conductors 1226 and 1227 which extend in multiple to brushes of the trunk selector switches. The transfer is now complete and circuit paths are established to operate the units relays in the indicating circuit, Fig. 2. A circuit is thus established from ground, through the right winding of marginal relay 214, right winding of sensitive relay 215, left outer normal contact of relay 219, left inner contact of relay 202, tip of plug 220, tip spring of jack 390, tip spring of jack 301, tip of plug 306, patching cord 311 and plug 316, tip spring of jack 1070, brush 1002 and its associated contact, fourth outer contact of relay 1028, conductor 1224, left outer contact of relay 1214, conductor 1227, conductor 1217, brush 1106 and its associated contact, conductor 1216, conductors 1231 and 1232, right contact of relay 1214, left inner contact of relay 1211, conductor 1031 to grounded battery through the left outer contact of relay 1027. Since the circuit traced includes no high resistance, both sensitive relay 215 and marginal relay 214

are energized. Both relays lock from grounded battery through their left windings and left inner contacts to ground over the sleeve of jack 220 as previously traced. Simultaneous with the circuit above traced for operating relays 214 and 215, a circuit is established from ground, through the left winding of sensitive relay 216, right normal contact of relay 219, right contact of relay 202, ring of plug 220, ring spring of jack 390, ring spring of jack 301, ring of plug 306, patching cord 311 and plug 316, ring spring of jack 1070, brush 1003 and its associated contact, third left contact of relay 1028, conductor 1225, left inner contact of relay 1214, conductor 1226, conductor 1218, brush 1107 and its associated contact, conductor 1215, left-hand low resistance winding of relay 1208, left normal contact of relay 1209, conductor 1232, right contact of relay 1214, inner left contact of relay 1211 to grounded battery through the left outer contact of relay 1027. Relay 216 operates and locks from grounded battery, through its right winding and right inner contact to ground through the sleeve of plug 220 as previously traced. Relay 1208 also operates in the circuit traced and establishes a circuit to operate relay 1209 from grounded battery, through the left outer contact of relay 1027, conductor 1031, left inner contact of relay 1211, right contact of relay 1214, conductor 1232, left normal contact of relay 1209, left contact of relay 1208, winding of relay 1209, conductor 1230 to ground through the left innermost contact of relay 1028, relay 1209 establishing a locking circuit for itself through its right contact over paths previously traced.

Upon the operation of either sensitive relay 215 or 216, a circuit is established to energize relay 219. This circuit may be traced from grounded battery, through the winding of relay 219, left outer contact of relay 215, right outer contact of relay 216 to ground through the contact of relay 230. The operation of relay 219 establishes circuits through its right and left contacts for the energization of relays 208 and 209. The operation of relay 219 further opens the energizing circuit for relay 1208 causing it to release its armatures. A circuit is now established from ground, through the right contact of relay 1209, right normal contact of relay 1208, conductor 1226, left inner contact of relay 1214, conductor 1225, third left contact of relay 1028, brush 1003 and its associated contact, ring spring of jack 1070, ring of plug 316, patching cord 311 and plug 306, ring spring of jack 301, ring spring of jack 390, ring of plug 220, right contact of relay 202, right contact of relay 219, windings of relays 208 and 209 to grounded battery operating relays 208 and 209.

With the lamp controlling relays operated

in the combination above described, the proper lamps are selected and illuminated for indicating the identity of the selected trunk to the test man. Since the number of the selector trunk is 31, it is necessary to illuminate the No. 0 lamp in the hundreds group, the No. 3 lamp in the tens group of lamps and the No. 1 in the units group of lamps. The circuit for lighting the No. 0 hundreds lamp may be traced from grounded battery through the left outer normal contact of relay 206, lamp 0, left inner contact of relay 219 to ground. The circuit for lighting the tens lamp 3 may be traced from grounded battery, through the right contact of relay 209, filament of the tens lamp 3, right inner contact of relay 205, left outer contact of relay 204 to ground through the left inner contact of relay 219. The circuit for lighting the No. 1 units lamp may be traced from grounded battery, through the left inner normal contact of relay 213, filament of the No. 1 units lamp, right inner contact of relay 214, left contact of relay 216, to ground through the left inner contact of relay 219. The test man observing the No. 31 displayed on the indicating lamps, knows that the trunk selecting apparatus has properly functioned.

In the manner hereinbefore described any trunk may be selected by the test man and the number indicated on the display set, Fig. 2. It will be noted that the contacts associated with brushes 1207 and 1107 are variously wired with relation to the windings of relay 1208 and that brushes 1206 and 1106 are variously wired with relation to the windings of relay 1280. With either brush 1206 or 1106 in certain positions, particular windings of relay 1208 are in circuit with the units relays to cause them to operate in a certain manner and to cause the operation of relay 1280. This circuit may be traced similarly to that traced for the operation of relay 1208. When relays 1280 and 1281 are operated in the manner described for the operation of relays 1208 and 1209, a circuit is established from ground, through the left contact of relay 1281 to operate relays 212 and 213 over a similar circuit to that traced for the operation of relays 208 and 209 to ground through the right contact of relay 1209.

If the trunk chosen is above No. 99, the hundreds relay 206 is operated by the association of a low resistance in series with its right winding. This low resistance is associated with relay 206 in a particular position of the side switch shown in Fig. 11.

It is apparent from the foregoing description that the operation of the link and trunk selecting apparatus may be tested and the result indicated upon the lamps of the testing circuit, also the progression

of said test indicated upon various lamps 65 in the testing circuit.

Upon the completion of the trunk number indication test, key 358 is operated by the test man to release the trunk indicating apparatus. The operation of key 358 opens the energizing circuit for relay 335 and the holding circuit for relay 353. Also, the actuating circuit for relay 1024 in the link is opened to cause its release. The release of relay 335 opens the holding circuit for 70 part of the operated trunk indicating relays shown in Fig. 2 to cause their release. The release of relay 335 further opens the circuit for lamp 336 which is extinguished. The release of relay 353 opens the actuating 75 circuit for relay 1211 and lamp 363 is extinguished to indicate the proper release of relay 1211. It will be remembered in the foregoing description that the operation of relay 1025 is prevented by a ground shunt 80 through the contact of relay 1024. Upon the release of relay 1024, this shunt is removed to cause the operation of relay 1025. The apparatus of the switching system is now restored to normal, as described in detail in the application of Louis M. Allen 85 previously mentioned in this description, and a complete restoration of the indicating apparatus shown in Fig. 2 is effected. Switch 1000 is prevented from restoring to 90 normal by the testing circuit. The normal path for the energization of magnet 1007 is opened by the insertion of plug 319 into jack 1073. Therefore, it is necessary to re-establish the energizing circuit for magnet 100 95 1007 in the testing circuit to restore switch 1000 to normal.

It will be remembered that relay 1019 is restored to normal along with other apparatus of the switching system. Relays 105 1008, 1020 and 1023, however, remain operated.

The test man may now maintain control of this link for other tests or restore to normal the remaining energized relays and switch 1000 by the operation of key 359. The circuit is established through the contacts of key 359 to energize relay 1021 from ground through its winding, sleeve of jack 1073, sleeve of plug 319, patching cord 314 110 115 and plug 309, sleeve of jack 304, upper contact of key 359, ring spring of jack 304, ring of plug 309, patching cord 314, and plug 319, ring spring of jack 1073, brush 1001 and its associated contact, right inner 120 contact of relay 1008, left outer normal contact of relay 1019 to grounded battery through the left winding of relay 1022. Relay 1022 operates and locks through its right winding over the path traced for its 125 energization until relay 1008 has released. The operation of relay 1021 opens the holding circuit for relay 1008 to cause its re-

lease. The release of relay 1008 opens the holding circuit for relay 1020 to cause its release also the release of relay 1008 establishes an energizing circuit for switch magnet 1007. This circuit may be traced from grounded battery through the winding and contact of magnet 1007, right inner normal contact of relay 1008, brush 1001 and its associated contact, ring spring of jack 1073, 5 ring of plug 319, patching cord 314 and plug 309, ring spring of jack 304, upper contact of key 359, sleeve of jack 304, sleeve of plug 309, patching cord 314 and plug 319, sleeve of jack 1073 to ground through 10 the right outer normal contact of relay 1020. Switch 1000 is now rotated one step 15 to its normal position.

Test of automatic switch control.

20 The testing apparatus shown in Fig. 2 may be used to actuate the apparatus of the switching system, including the sender, to control automatic selector switches and direct them to a test line. The trunk is selected in the manner described for a trunk indicating test, and upon the selection of said trunk, plug 364 is inserted into jack 349 and plug 352 inserted in plug 1252.

It will be remembered that in the previous 25 test relay 1211 is under the control of the testing circuit. In this test, it is desirable to associate the operating circuit of relay 1211 with the trunk hunting brush 1103 so that relay 1211 will be operated when an idle trunk is encountered and will not be operated when busy trunks are encountered. This is in accordance with the normal functions of relay 1211. Upon the association 30 of the link with said idle trunk, the operation of relay 1211 establishes a circuit to operate relay 338 and light lamp 363 to indicate to the test man that the idle trunk has been found. The circuit for operating relay 338 and lighting lamp 363, may be 35 traced from ground through the left outer contact of relay 1211, tip spring of jack 1251, tip of plug 367, tip conductor of patching cord 369, tip of plug 365 and tip spring of jack 350, filament of lamp 363 to grounded battery and also traced from the tip 40 spring of jack 350, through the upper contact of jack 349, right contacts of relay 337, which is in an operated position, winding of relay 338 to grounded battery. The 45 operation of relay 338 establishes a circuit path which will be described upon the operation of key 347.

50 Relay 1308 is energized in the manner described during the trunk selection test and serves to initiate the movement of the sender selector switch 1300 to select an idle register sender. The operation of relay 1308 establishes a circuit from grounded battery, through the right winding of relay 1312,

inner right normal continuity contact of relay 1313, right inner contact of relay 1308, right contact of relay 1309 to ground. Relay 1312 energizes and establishes a locking circuit for itself to ground on contacts of switch 1300 during the period that the 55 switch is hunting other busy register senders. This circuit may be traced from grounded battery, through the left winding and left contact of relay 1312, left outer contact of relay 1308, test brush 1307 and its associated contacts, to ground. Relay 1312 during its period of energization establishes a circuit to operate relay 1313 from grounded battery, through its winding, right contact of relay 1312 to ground. The operation of 60 relay 1313 establishes a locking circuit for itself from grounded battery through its winding and right inner contact, right inner contact of relay 1308 to ground at the right contact of relay 1309. The operation 65 of relay 1313 opens the energizing circuit through the right winding of relay 1312 whereby this relay is now dependent for its continued energization upon the test circuit through its left winding and test brush 70 1307. When relays 1312 and 1313 energize, a circuit is established from grounded battery through the winding and contact of the stepping magnet 1301, right outer contact of relay 1313, right contact of relay 75 1312 to ground. Magnet 1301 operates to rotate the brushes of switch 1300 under the control of its self-interrupting contact and the ground encountered upon contacts associated with test brush 1307 that are characterized as busy by other senders.

When brush 1307 encounters an idle sender the associated contact is not characterized by ground and the holding circuit for relay 1312 is opened to cause its de-energization. The deenergization of relay 80 1312 opens the actuating circuit for magnet 1301 to arrest the rotary movement of the switch. Relay 1313 remains energized and a circuit is established to operate relay 1314 85 from ground through the left contact of relay 1313, winding of relay 1314, left normal contact of relay 1312, left outer contact of relay 1308, brush 1307 and its associated contact, conductor 1324, left outer contact 90 of relay 1400, thence in parallel through the resistance 1402, and the winding of relay 1401 to battery. The operation of relay 1314 establishes a circuit from grounded battery through the winding of relay 1315, 95 right continuity contact of relay 1316, contact of relay 1314 to ground. Relay 1315 operates and establishes a circuit from grounded battery, through its winding and the winding of relay 1316 in series, left inner contact of relay 1315, left inner contact of relay 1308 to ground. Relay 1316, however, cannot operate at this time since its 100

winding is shunted by a direct path to ground at the contact of relay 1314. Relay 1316 does, however, operate upon a subsequent deenergization of relay 1314.

6 The operation of relay 1315 establishes a circuit to operate relay 1029 from grounded battery, through its winding, right outer contact of relay 1027, right outer normal contact of relay 1318, left outer contact of relay 1315, left inner contact of relay 1308 to ground. Relay 1029 at its armatures and contacts extends three conductors 1320, 1321, 1322 from the selected register sender over brushes 1004, 1005 and 1006 to the testing unit. The operation of relay 1315 further establishes a circuit to operate relay 1210 from grounded battery through the winding of relay 1210, contact of jack 1252, left inner continuity contact of relay 1210, right contact of relay 1315 to ground through the left innermost contact of relay 1028 which is in an operated position.

At the time an idle sender is selected a circuit is established to operate relay 331 in the testing circuit from ground, through the middle contacts of key 358, winding of relay 331, normal contact of relay 330, ring spring of jack 305, ring of plug 310, ring of patching cord 315, ring of plug 320, ring spring of jack 1074, brush 1005 and its associated contact in position 20, right middle spring of relay 1029, conductor 1321, brush 1305 and its associated contact, conductor 1415, brush 1412 and its associated contact in position 1, left winding of relay 1602, left winding of relay 1603 to grounded battery, through the left middle contact of relay 1403 which is in an operated position, relay 1403 having operated upon the energization of relay 1401. Relay 331 operates in the circuit traced, but on account of the high resistance of the winding of relay 331, relays 1602 and 1603 do not operate. Relay 331 establishes a locking circuit for itself to grounded battery through its contacts. The operation of relay 331 further establishes an obvious circuit to light lamp 332 and to operate relay 330. The operation of relay 330 transfers conductor 394 from the operating circuit of relay 331 to the registration keys 380 to 389.

When the test man observes the lighting of lamp 332, he proceeds to depress the proper ones of the non-locking keys 380 to 389 representing the number of the test line to which the final selector switch is to be directed. Assuming this number to be 1647, the test man actuates the key 381, key 386, key 384, and key 387. These keys are operated in succession and the sender apparatus is progressively positioned to operate the register relays as rapidly as the keys are depressed. The depression of key 381 completes a circuit from ground through the lower contacts of jack 349, resistance

374, right contact of key 381, contact of relay 330, conductor 394, ring spring of jack 305, ring of plug 310, patching coil 315, and plug 320, ring spring of jack 1074, brush 1005 and its associated contact, middle contact of relay 1029, conductor 1321, brush 1305 and its associated contact, conductor 1415 brush 1412 and its associated contact, conductor 1416, left winding of relay 1602, left winding of relay 1603, conductor 1613 to grounded battery at the middle left contact of relay 1403. Relay 1602 operates in this circuit but on account of the inclusion of resistance 374, the marginal relay 1603 remains inert. Relay 1602 locks in a circuit from ground through its right inner contact and right winding to grounded battery on conductor 1613. Another circuit is completed from ground through the contacts of jack 349, left contacts of key 381, tip spring of jack 305, tip of plug 310, patching cord 315 and plug 320, tip spring of jack 1074, brush 1004 and its associated contact, outermost right contact of relay 1029, conductor 1320, brush 1304, winding of relay 1404, brush 1410, and its associated contact, conductor 1417, right winding of relay 1601 to grounded battery on conductor 1613. Since no resistance is included in this circuit, the marginal register relay 1601 operates and locks through its inner left contact and both windings. Relay 1600 is also energized in a circuit from grounded battery on conductor 1613, right winding of relay 1600, right inner contact of relay 1601, right inner contact of relay 1602 to ground. Relay 1404 which also becomes energized completes a circuit from ground, through its front contact, left back contact of relay 1407, right back contact of relay 1400, contact and winding of stepping magnet 1408 to grounded battery. Relay 1406 which is energized in parallel with the stepping magnet closes a locking circuit for itself including the contact magnet 1408 and also closes a holding circuit for magnet 1408 independent of the contact of relay 1404. The magnet 1408 becomes energized, and when its armature is fully attracted, the circuit of relay 1406 is opened, and this relay becomes deenergized to in turn open the circuit of magnet 1408. Magnet 1408 releases and advances the brushes of the register control switch forward one step to their next terminals.

When the register control switch is advanced, a circuit is established from grounded battery, through the winding of relay 1503, left contact of relay 1502, conductor 1516, brush 1409 and its associated contact to ground. Relay 1503 operates and establishes a circuit from ground through its left inner contact, conductor 1517, and thence in parallel through the resistance 1402 and the winding of relay 1401 to

grounded battery shunting relay 1314 which thereupon deenergizes. With relay 1314 deenergized the shunt is removed from relay 1316 permitting this relay to energize 5 in series with relay 1315.

When the test man depresses key 386, a circuit is established from ground, through the contacts of jack 349, resistance 374, right contact of key 386, contact of relay 330, ring 10 spring of jack 305, ring of plug 310, patching cord 315 and plug 320, ring spring of jack 1074, brush 1005 and its associated contact, and thence as above traced to conductor 1415, brush 1412, and its associated contact, 15 conductor 1418, left winding of relays 1605 and 1606 to grounded battery on conductor 1613. Relay 1605 operates and locks through its right winding, but the relay 20 1606 remains inactive since it is of the marginal type. Another circuit is established from ground through the contacts of jack 349, left contact of key 386, sleeve of jack 305, sleeve of plug 310, patching cord 315 and plug 320, sleeve of jack 1074, brush 25 1006, and its associated contact, and thence to brush 1306, winding of relay 1405, brush 1410, conductor 1419, right winding of relay 1604 to grounded battery on conductor 1613. Relay 1604 operates and locks 30 through its left inner contact. Relay 1405 also energizes to cause the advance of the register control switch in the manner above described. Relay 1405 further establishes a circuit from ground through its contact normal 35 contact of relay 1404, brush 1414 and its associated contact, conductor 1420, right winding of relay 1607 to grounded battery on conductor 1613. Relay 1607 operates and locks through its left winding and left contact. 40

Upon the depression of key 384, a circuit is established from ground through the contacts of jack 349, right contact of said key, contact of relay 330, ring spring of jack 45 305, thence over the path previously traced to brush 1412 and its associated contact, conductor 1421, left winding of relay 1614, left winding of relay 1609, conductor 1615, innermost left contact of relay 1403 to 50 grounded battery. Relays 1614 and 1609 operate and lock through their right windings. Another circuit is established from ground through the contacts of jack 349, resistance 373, left contacts of key 384, tip 55 spring of jack 305, tip of plug 310, patching cord 315 and plug 320, tip spring of jack 1074, brush 1004 and its associated contact, right outermost contact of relay 1029, brush 1304 and its associated contact, winding of relay 1404, brush 1410, conductor 1422, right winding of relay 1613 to 60 grounded battery. Relay 1404 operates, but since relay 1608 is marginal it remains inactive. In the manner above described, the 65 operation of relay 1404 causes the advance

of the register control switch. Upon the actuation of key 387, a circuit is established from ground, through the contact of jack 349, left contacts of said key to the sleeve of jack 305, thence over the path previously traced to the winding of relay 1405, brush 1410, conductor 1423, right winding of relay 1610, conductor 1615 to grounded battery. Relay 1610 operates and locks through both of its windings. Relay 1405 operates and 70 establishes a circuit through its contact and the contact of relay 1404, brush 1414, and its associated contact, conductor 1424, right winding of relay 1612, conductor 1615 to grounded battery. Relay 1612 operates and locks through its left winding and left contact. Relay 1405 also causes the advance of 75 the register control switch.

As brush 1409 of the control switch advances, the previously traced actuating circuit for relay 1503 is opened and this relay deenergizes to remove the shunt from around the winding of relay 1314. Relay 1314 again attracts its armature, and a circuit is established from ground through the contact of this relay, outer right front contact of relay 1316, winding of relay 1317 to grounded battery. Relay 1317 operates and establishes a circuit from grounded battery through its winding and the winding of relay 1318, left contact of relay 1317 to ground at the inner contact of relay 1318. Relay 1318, however, cannot operate at this time, since it is shunted by the direct circuit to ground at the contact of relay 1314. 85 Relay 1318 is operated upon the completion of control of the selective switches by the sender, as will hereinafter be described. 90

Following the registration of the first digit, the sender control of the selective 95 switches is started. At this time, relay 1103 operates and a circuit is established from grounded battery, through the stepping magnet 1513 of the sender control switch contact of said magnet, left outer 100 contact of relay 1503, normal position terminal of brush 1509 to ground. Magnet 1513 interrupts its own circuit and advances the brushes of the sender control switch to their first position for the control of selective 105 switch selections. In this position, the fundamental circuit for control of brush selection of the incoming selector 1153 in the distant mechanical office is closed. The fundamental circuit which is well known in 110 systems of this character may be traced from the incoming selector over the trunk conductor 1156, conductor 1158, brush 1104 and its associated contact, conductor 1109, middle right contact of relay 1210, brush 125 1303 and its associated contact, conductor 1425, brush 1507, and its associated contact, winding of the stepping relay 1500, left winding of overflow relay 1506, left contact 130 of the 0' counting relay, conductor 1518, 130

brush 1302 and its associated contact, right outermost contact of relay 1210, conductor 1111, brush 1105 and its associated contact, conductor 1158, trunk conductor 1156, and thence to the opposite pole of battery at the incoming selector switch 1153. On account of the direction of flow of current, the overflow relay 1506, which is polarized, does not operate in the fundamental circuit. The 10 stepping relay 1500 attracts its armature and establishes a circuit through its contact, brush 1508 and its associated contact, conductor 1519, right contact of relay 1615, right outer contact of relay 1600, left contact of relay 1603, conductor 1616, thence to the corresponding conductor 1520, conductor 1521, brush 1512 and its associated contact, conductor 1522, winding of the zero counting relay to grounded battery. The 15 zero counting relay operates and closes a circuit from grounded battery, through its winding and the winding of relay 1515 in series, contact of relay 1514, conductor 1523, brush 1510 and its associated contact to ground. In the well known manner, the first shunt of the stepping relay 1500 by the actuation of the incoming selector switch 1153 permits the energization of the 0' counting relay to open the fundamental circuit and also to establish a circuit from grounded battery, through the winding and contact of stepping magnet 1513, right inner contact of relay 1505, right contact of relay 1515, conductor 1523 to ground. Magnet 1513 operates to advance the sender switch brushes to their next position and the counting relays become deenergized. In this position of the switch, a circuit is established from grounded battery, through the winding and contact of magnet 1513, outer contact of relay 1504, brush 1510 and its associated contact to ground. Magnet 1513 operates and advances the sender switch to its next position of control.

The fundamental circuit is again established and incoming group selection takes place in switch 1153 in accordance with the energized condition of the register relays. At the termination of group selection, 0' counting relay again opens the fundamental circuit and at its right contact establishes the circuit above traced for rotating the sender control switch. The incoming selector switch hunts for an idle trunk, and when this is selected, the fundamental circuit is again established for brush selection, at the final selector switch 1154. Stepping relay 1500 is successively shunted and the counting relays operate in accordance with the energized condition of the register relays until the proper set of brushes have been reached, at which time the fundamental circuit is opened by the 0' counting relay and a circuit is established, as explained for driving the sender control

switch to its next control position. In the manner described, the final selector switch is controlled to make tens and units selection to associate its brush members with an auxiliary testing apparatus 1155. Following final unit selection, the incoming selector switch is advanced to its trunk closure position in the well known manner. 70

As soon as the registration keys have been operated to control the registration in the sender, the test man operates key 347 to simulate the insertion of the cord circuit plug into the outgoing trunk jack. A circuit is established from grounded battery, through the winding of relay 348, right inner contact of key 347, contact of relay 338, sleeve of jack 349, sleeve of plug 364; patching cord 368 and plug 352, sleeve of jack 1252, right innermost contact of relay 1210, winding of relay 1310 to ground. Relay 1310 operates in the circuit traced but due to the high resistance of the winding of the relay 1310, the relay 348 does not operate at this time. Since relay 348 simulates the application of grounded battery through plugging up a cord circuit, it is necessary to prevent its operation until the sender has completed the control of the selective switches. 75 80 85 90 95

It will be remembered that a ground shunt through the contact of relay 1314 is maintained around the winding of relay 1318 to prevent its operation. At the time that relay 1400 becomes energized to cause the release of the register sender, as previously described, it opens the previously traced circuit for relay 1314. The release of relay 1314 removes the shunt from around the winding of relay 1318 and this latter relay operates in series with relay 1317. The circuit hereinbefore traced through the winding of relay 348 and high resistance relay 1310 is now so multiplied that a circuit path is established over the left contact of relay 1311, left low resistance winding of relay 1309, left contact of relay 1318 to ground. Relay 1309 operates and on account of the comparative low resistance of this path, relay 348, now operates. The operation of relay 1309 opens the holding circuit for relay 1308 which is released. The release of relay 1308 opens the circuits for relays 1313, 1315, 1316, 1317 and 1318.

The operation of relay 348 establishes a circuit from grounded battery, through the winding of relay 360, right outer contact of relay 348, ring spring of jack 349, ring of plug 364, patching cord 368 and plug 352, ring spring of jack 1252, brush 1105 and its associated contact, conductor 1159, trunk 1157, and thence through the incoming selector switch. A circuit is further established by the operation of relay 348 to associate ground with the tip of incoming trunk. This circuit may be traced from

ground through the right inner contact of relay 348, tip spring of jack 349, tip of plug 364, patching cord 368 and plug 352, tip spring of jack 1252, brush 1104 and its associated contact, conductor 1158, trunk conductor 1156 to the incoming selector switch. Trunk closure is now effective for the incoming selector switch which responds in the well known manner and is advanced to the 10 position for ringing a subscriber. The operation of relay 348 further establishes a locking circuit for itself and a shunt path to release relay 1211. The locking circuit is obvious and need not be traced. The shunt path may be traced from ground through the left inner contact of key 347, left contact of relay 348, left middle contact of relay 353, resistance 375 to grounded battery. The grounded battery through resistance 375 is serving to maintain relay 1211 operated and since the ground shunt is placed between the relay winding and the battery relay 1211 is released.

A detailed description of the auxiliary 25 testing apparatus 1155 is made in the application to Arnold S. Bertels Serial No. 653, 125, filed July 23, 1923, and therefore will not be covered in this application. In general, this auxiliary testing apparatus 1155 30 serves to test the ringing apparatus of the incoming selector switch and advance said incoming selector switch to its talking position. When the incoming selector switch is in the talking position, its supervisory relay is operated and released a number of times by the operation of the auxiliary testing apparatus 1155. The operation and release of the supervisory relay in the incoming selector switch serve 40 to operate and release relay 360 in the testing circuit. Each release of relay 360 establishes a circuit to light lamp 361 from grounded battery through its filament, normal contact of relay 360, left contact of relay 348 to ground through the left inner contact of key 347. The flashing of lamp 361 indicates to the test man that the switching system has properly functioned to direct the 45 incoming and final selector switches to the test line, under the control of particular ones of the registration keys 380 to 389 that were 50 operated to direct the call.

The test man now restored key 347 to normal which releases relays 348 and 360 and 55 extinguishes the supervisory lamp 361. Keys 358 and 359 are now operated to release the relays of the testing circuit and the patching cords and plugs are removed from the various jacks to disassociate the testing circuit 60 from the switching system.

Switchboard test of trunk indicating apparatus.

The testing unit shown in Fig. 1 is such 65 that it may be carried by the test man to the

positions of the switchboard. Jack 930 is located in the face of the switchboard. The test is made in order to observe the trunk number indicated by the lamps after said number is transmitted to the indicating relays by the operation of certain of the keys shown in Fig. 1. Upon the operation of certain of the keys, should the trunk number indicated by the lamps shown in Fig. 9 not agree with the keys actuated, it is apparent 75 that the relays of the trunk indicating circuit did not properly respond to the circuit paths established.

The test man inserts plug 151 into jack 930, which jack is representative of the jack 80 in any position of the switchboard. A circuit is established from grounded battery through the upper springs of jack 930, lamp 931 to ground through the left outer contact of relay 902. This lamp is used in service 85 operation to indicate that no outgoing trunk has been found by the link. The test is to ascertain the proper illuminating qualities of the lamp. Key 150 is now actuated by 90 the test man. A circuit is thus established to operate relay 127 from grounded battery, through its winding to ground through the upper springs of key 150. This ground is also extended over the sleeve of plug 151, sleeve of jack 930 and to the armatures of 95 certain of the trunk indicating relays to be used later as part of the holding circuit for said relays. This ground is further extended from the sleeve of jack 930 through the middle upper springs of said jack to armatures of other of the trunk indicating 100 relays. The operation of relay 127 is used to associate the testing circuit with a trunk indicating circuit. The purpose in having this relay is to allow plug 131 to be inserted 105 in the jack 930 of a busy indicating circuit. However, key 150 is not operated until the indicating circuit is idle.

Let it be assumed that the trunk number to be indicated is "126". The hundreds key 110 140, the tens key 102 and the units key 116 are operated by the test man. The operation of the hundreds key 140 and the tens key 102 establish circuits for hundreds and tens relay operation in the indicating 115 circuit. A circuit may be traced from ground through the left low resistance winding of relay 120, key 140, left contacts of key 102, left normal contact of relay 122, resistance 120, right contact of relay 127, ring of plug 151, ring spring of jack 930, conductor 900, right normal contact of relay 902, left winding of relay 904, left winding of relay 906 to grounded battery. On account of the low 125 resistance of the circuit path through the left winding of relay 120 both the sensitive relay 904 and the marginal relay 906 operate. Another circuit may be traced from ground through resistance 131, right contact of key 102, right normal contact of relay 130

122, resistance 132, left contact of relay 127, tip of plug 151, tip spring of jack 930, conductor 901, inner left contact of relay 902, left winding of relay 903, left winding of relay 905 to grounded battery through the upper spring of jack 930. Resistance 131 is low and therefore both sensitive relay 903 and marginal relay 905 operate in the circuit traced. Relay 120 is operated in the circuit traced through its left winding to establish an obvious operating circuit for relay 121. The operation of relay 121 establishes a locking path for itself through its left contact to ground through the lower contact of key 150. A circuit is established to light lamp 142 from grounded battery through its filament to ground through the lower contact of key 150.

A circuit is established to operate relay 902 when either or both relays 903 and 904 operate. The operation of relay 902 transfers the control leads from the hundreds and tens relays of the indicating circuit to the units relays. It will be noted that the operating windings of the unit relays are carried to ground and thus the operating circuit for relay 120 is opened to cause its release. The release of relay 102 establishes an energizing path for relay 122 from ground through the right normal contact of relay 120, right contact of relay 121, winding of relay 122 to grounded battery. The operation of relay 122 transfers the control circuit from the hundreds and tens keys to the units keys 110 to 119. Since the test man operated key 116 for this representative test, a circuit may be traced from grounded battery through resistance 135, left contact of relay 126, right contact of key 116, right contact of relay 122, resistance 132, left contact of relay 127, tip of plug 151, tip spring of jack 930, left inner contact of relay 902, right inner normal contact of relay 919, left winding of relay 915, left winding of relay 914 to ground. Since resistance 135 is low the operation of both the sensitive relay 915 and marginal relay 914 takes place. Simultaneous with the circuit traced from resistance 135, a circuit is established from grounded battery through the right winding of relay 123, left contact of key 116, left contact of relay 122, resistance 133, right contact of relay 127, ring of plug 151, ring of jack 930, conductor 900, right contact of relay 902, left normal contact of relay 919, left winding of relay 916 to ground.

Sensitive relay 916 and relay 123 are operated in the circuit traced. Upon the operation of relays 903, 904, 915 and 916, locking circuits are established from grounded battery through their right windings and associated right contact, through contact springs and sleeve of jack 930, sleeve of plug 151 to ground through the upper contact of key 150. Upon the operation of relays 905, 906 and 914, locking circuits are established from grounded battery through their right windings and associated right contact, sleeve of jack 930, 70 sleeve of plug 151 to ground through the upper contact of key 150.

The operation of either of both relays 915 or 916 establishes an obvious circuit to operate slow-acting relay 917. The operation of relay 917 establishes an obvious circuit to operate slow-acting relay 918 and the operation of relay 918 establishes an obvious circuit for relay 919. During the operation of relays 917, 918 and 919, a circuit is established to operate relay 124 from ground battery through its winding, contacts of relay 123 to ground through the lower contacts of key 150. The operation of relay 124 establishes a locking circuit for itself through its right contact to ground through the lower contact of key 150 which same ground circuit is established through the filament of lamp 141 to grounded battery to light lamp 141.

The operation of relay 919 transfers the control conductors from the windings of the units relays to the lamp relays 908, 909, 912 and 913. It will be noted that the windings of these relays are connected to battery and thus the transfer opens the actuating circuit for relay 123 to cause its release. The release of relay 123 establishes a circuit to operate relays 125 and 126 from grounded battery through their windings 95 in multiple and through the left contact of relay 124, right normal contact of relay 123 to ground through the lower contact of key 150. The operation of relay 125 establishes a locking path for itself from grounded battery through its winding, left inner contact to ground through the lower contact of key 150. The operation of relay 126 establishes a circuit to operate relays 912 and 913. This circuit may be traced from ground through the left contact of relay 126, right contact of key 116, right contact of relay 122, resistance 132, left contact of relay 127, tip of plug 151, spring of jack 930, left inner contact of relay 902, right inner contact of relay 919, windings of relays 912 and 913 to grounded battery, operating relays 912 and 913. The keys operated for trunk No. 126 do not establish an operating path for relays 908 and 909 100 and therefore they remain inactive.

Circuits have now been established to light the hundreds lamp 1, the tens lamp 2 and the units lamp 6. The circuit to operate the hundreds lamp 1 may be traced from grounded battery through the left contact of relay 906, filament of hundreds lamp 1 to ground through the right outer contact of relay 919. The circuit for lighting tens lamp 2 may be traced from ground- 105

110

115

120

125

130

ed battery through the left outer normal contact of relay 908, filament of lamp 2, left outer contact of relay 905, left outer contact of relay 904 to ground through the 5 right outer contact of relay 919. The circuit for lighting units lamp 6 may be traced from grounded battery through the right contact of relay 912, filament of units lamp 6, left outer contact of relay 914, left outer 10 contact of relay 916 to ground through the right outer contact of relay 919.

Upon the successful operation of the indicating apparatus and the illumination of the trunk number lamps, key 150 is released to open the holding circuit for the indicating relays and the relays of the testing circuit. If it is desirable to make a second test upon the same indicating circuit, key 150 is re-operated and the hundreds, tens and units keys are actuated in accordance with the trunk number to be displayed. When the test man is satisfied with the operation of an indicating circuit plug 151 is removed.

25 What is claimed is:

1. In a testing system to test a sender having a plurality of registers, means to control particular settings of the registers in said sender, a switch, means to revolve said switch and means to consecutively operate said plurality of registers during a single continuous revolution of said switch.

2. In a testing system to test a sender having a plurality of registers, means to control particular settings of the registers in said sender, a switch, means to revolve said switch, means to consecutively operate said plurality of registers during a single continuous revolution of said switch and 40 means to test whether said registers operate as directed by said control means.

3. In a testing system to test a sender having a plurality of registers, means to control particular settings of the registers in said sender, a switch, means to revolve said switch, means to consecutively operate said plurality of registers during a single continuous revolution of said switch, means to test whether said registers operate as directed by said control means and means to indicate whether said registers operate as directed by said control means.

4. In a testing system to test a sender having a plurality of registers, means to control particular settings of the registers in said sender, a switch, means to revolve said switch, means to consecutively operate said plurality of registers during a single continuous revolution of said switch, means to 50 progressively operate said sender, means to restore said sender to normal and means to indicate whether said sender is restored to normal or left in an off-normal position.

5. In a testing system to test a plurality 55 of senders each having a plurality of regis-

ters, means to select any one of said senders, means operable to control particular settings of the registers in the selected sender, a switch, means to revolve said switch and means to consecutively operate said plurality of registers during a single continuous revolution of said switch. 70

6. In a testing system to test a sender having a plurality of registers, means operable to control particular settings of the registers in said sender, a switch, means to revolve said switch, means to consecutively operate said plurality of registers during a single continuous revolution of said switch, 75 means to progressively operate said sender and checking means progressively operated in accordance with the progressive operation of said sender and in accordance with the settings of said registers. 80

7. In a testing system to test a sender having a plurality of registers, means operable to control particular settings of the registers in said sender, a switch, means to revolve said switch, means to consecutively operate said plurality of registers during a single continuous revolution of said switch, 85 means to progressively operate said sender, checking means progressively operated in accordance with the progressive operation of said sender and in accordance with the settings of said registers and means to arrest the progressive operation of said checking means and sender when said registers have assumed settings not in accordance with said control means. 90

8. In a testing system to test a sender having a plurality of registers, means operable to control particular settings of the registers in said sender, a switch, means to revolve said switch, means to consecutively operate said plurality of registers during a single continuous revolution of said switch, 95 means to progressively operate said senders, checking means progressively operated in accordance with the progressive operation of said sender and in accordance with the settings of said registers, means to arrest the progressive operation of said checking means and sender when said registers have assumed settings not in accordance with said control means and means to indicate what particular register has assumed a setting not in accordance with said control means. 100

9. In a testing system to test a sender having a plurality of registers, means operable to control particular settings of the registers in said sender, a switch, means to revolve said switch, means to consecutively operate said plurality of registers during a single continuous revolution of said switch, 105 means to progressively operate said sender, checking means progressively operated in accordance with the progressive operation of said sender and in accordance with the settings of said registers, means to arrest the progressive operation of said sender, checking means progressively operated in accordance with the progressive operation of said sender and in accordance with the settings of said registers, means to 110 indicate what particular register has assumed a setting not in accordance with said control means. 115

120

125

130

gressive operation of said checking means and sender when said registers have assumed settings not in accordance with said control means and means to indicate the manner of setting assumed by a particular register.

- 5 10. In a testing system, a testing unit for testing a link arranged for selecting any of a plurality of trunks, a plurality of switches within said link, means to select a particular one of said switches, means to operate said switch to select said testing unit, means to operate said link for selecting a particular trunk and means to indicate the number of the trunk so selected.
- 15 11. In a telephone exchange system, a testing unit for testing a link arranged to select any one of a plurality of trunks and any one of a plurality of senders, a plurality of switches within said link, means to select a particular one of said switches, means to op-

erate said switch to select said testing unit, means to operate said link for selecting a particular trunk, means to operate said link for selecting an idle sender, selective switches, a test line, means to operate said sender for directing selective switches to a test line and signaling means to indicate when such operation is accurately completed.

20 12. In a testing system arranged to test a trunk indicating apparatus ordinarily operated to indicate the number of a trunk automatically selected, means to control arbitrarily said trunk indicating apparatus to indicate any trunk number within its scope and means to indicate the progressive operation of said indicating apparatus.

In witness whereof, I hereunto subscribe my name this 5th day of May A. D., 1924.

JOHN B. RETALLACK.
